UNITED STATES PATENT OFFICE

157,606

WRIST WATCH CASE OR THE LIKE

Richard Max Lachman, Seattle, Wash.

Application August 25, 1948, Serial No. 148,292

Term of patent 14 years

(Cl. D42—8)

To all whom it may concern:

Be it known that I, Richard Max Lachman, a citizen of the United States of America, residing at Seattle, in the county of King and State of Washington, have invented a new, original, and ornamental Design for a Wrist Watch Case or the like, of which the following is a specification, reference being had to the accompanying drawing, forming part thereof.

The broken line showings in Figures 1 and 2 are for illustrative purposes only.

I claim:

The ornamental design for a wrist watch case or the like, substantially as shown and described.

RICHARD MAX LACHMAN.
